[57] CLAIM

The ornamental design of a cover for a pedestal mounted bowling scorer, as shown and described.

DESCRIPTION

FIG. 1 is a perspective view of a cover for a pedestal mounted bowling scorer showing our new design; FIG. 2 is a right side view of the cover of FIG. 1; FIG. 3 is a front view of the cover of FIG. 1; FIG. 4 is a top view of the cover of FIG. 1; FIG. 5 is a back view of the cover of FIG. 1; FIG. 6 is a left side view of the cover of FIG. 1; and, FIG. 7 is a bottom view of the cover of FIG. 1.

The broken line showing of a bowling scorer is for illustrative purposes only and forms no part of the claim.
